(57) **CLAIM**

The ornamental design for a fixture for delivering interconnect members onto a substrate, as shown and described.

DESCRIPTION

FIG. 1 is a top perspective view of a fixture for delivering interconnect members onto a substrate, with a base plate shown in broken lines, showing my new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front side view thereof;

FIG. 8 is a rear side view thereof;

FIG. 9 is a top exploded perspective view thereof;

FIG. 10 is a bottom exploded perspective view thereof; and, FIG. 11 is a bottom view of a top plate of the fixture for delivering interconnect members onto a substrate, in which the base plate in broken lines is removed for ease of illustration.

The broken lines depict environmental features that form no part of the claimed design, including the array of openings in the center of the top plate.
